Application August 2, 1940, Serial No. 349,618

15 Claims.

(Cl. 99—259)

This invention relates to a unit air conditioner and more particularly to such a unit for maintaining the proper temperature, humidity, pressure, air movement of both primary and secondary air, and smoke density of the smoke laden air in a smokehouse in which food products are being cured and smoked although the unit air conditioner forming the subject of the invention can also be employed in the processing of other materials, such as in drying leather.

One of the principal objects of the invention is to provide a compact and simple air conditioning unit containing the necessary mechanisms for supplying air to a smokehouse or similar enclosure in which materials are processed; varying the amount and velocity of the air so supplied to obtain the desired movement of both the primary and secondary air within the enclosure; introducing smoke to the air so supplied when required; heating the air so introduced when required; withdrawing air from the enclosure to maintain the desired static pressure in the smokehouse; returning a part of the air so withdrawn, together with outside air, to the smokehouse to maintain the desired humidity therein; and humidifying the air supplied to the enclosure, when required. By the provision of these various instrumentalities in a single compact unit, installation of the equipment is greatly simplified and the greater part of the fabrication can be effected at the factory instead of in the field; heat losses are reduced, resistance to air flow is minimized; the danger of leakage can be completely eliminated; the amount of floor and overhead space required for the equipment can be greatly reduced; the amount of materials necessary for the equipment can be reduced thereby lowering the cost of the equipment and permitting of the use of more costly materials and finer finishing; inspection and repair of the equipment is facilitated especially where a battery of identical units are in use in a packing plant; and an extremely sensitive control of the condition and movement of the air within the smokehouse can be readily obtained.

Another object of the invention is to provide such a unit which is substantially the same height as the smokehouse and can be placed flush against the rear wall of the smokehouse thereby to simplify and reduce the amount of ductwork necessary to connect the unit with the overhead ducts of the smokehouse.

Another object is to provide such a unit which can also be mounted horizontally thereby to permit of mounting the unit on top of or underneath

the smokehouse where the conditions encountered render such mounting of the unit desirable.

Another purpose is to provide such a unit which is composed of two readily separable major sections thereby to facilitate shipping of the unit to the location and to facilitate the transportation of the unit through doors, corridors and elevators in getting the unit into location within the packing plant.

10 Another object is to provide such a unit in which all danger of outside air, return air, and smoke laden air short circuiting in the unit is avoided thereby insuring accurate control of the conditions within the smokehouse.

15 Another aim is to introduce the smoke laden air into the unit in such manner as to reduce to a minimum the fouling of the equipment by creosote deposits thereby to eliminate the necessity of frequent cleaning, particularly of the finned heating surface from which a creosote deposit is difficult to remove.

20 Another object is to provide such a unit in which all of the interior parts of the unit are readily accessible through conveniently removable access panels thereby facilitating inspection, adjustment, repair and cleaning of the unit when required.

25 Another object of the invention is to provide such a unit which is mounted on removable feet to facilitate the transportation of the unit to its place of installation and also to permit of readily varying the overall height of the unit and the height of the various duct openings thereby to facilitate the ductwork construction.

30 Another purpose is to provide such a unit in which the supply fan section of the casing for the unit can be readily mounted to provide for a discharge of the fan from either of two diametrically opposite sides of the casing thereby rendering the unit readily adaptable to installation when peculiar conditions are encountered.

35 Another object is to provide such a unit from which any water of condensation is readily drained and in which water for humidification is readily introduced.

40 Another object is to arrange the motor controlled dampers in the ductwork between the unit and the smokehouse to provide flexibility in supplying any make or form of control desired by the packer.

45 Other objects and advantages of the unit forming the subject of this invention will appear from the following description and the accompanying drawings wherein:

50 Fig. 1 is a side elevation of a smokehouse

equipped with the air conditioning unit forming the subject of the present invention and showing a part of the smokehouse broken away to disclose the interior tracks and overhead ductwork thereof.

Fig. 2 is a vertical transverse section through the smokehouse, this section being taken on line 2—2, Fig. 1.

Fig. 3 is a vertical section through the air conditioning unit illustrated in Figs. 1 and 2, this section being taken on line 3—3, Fig. 4.

Fig. 4 is a vertical section taken on line 4—4, Fig. 3.

Fig. 5 is a side elevation of the air conditioning unit.

Fig. 6 is a diagrammatic representation of the control instruments used in connection with the air conditioning unit to regulate the temperature, humidity and static pressure of the air within the smokehouse.

While the air conditioning unit embodying the present invention can be used in connection with any type of smokehouse, the smokehouse illustrated is of the insulated panel type of construction having side walls 10, 11, a roof 12, a rear wall 13 and a front wall 14 having an access door 15 which can be mounted in any suitable manner. The smokehouse is shown as provided with an overhead track 20 which is suspended in any suitable manner from rods 21, these rods being preferably suspended from the ceiling (not shown) of the packing plant so that the smokehouse can be made of light construction. With such a smokehouse the food products to be cured and smoked can be hung from trees (not shown) suspended from the overhead track 20 or can be hung upon trucks (not shown).

The air is introduced into the smokehouse through a central overhead duct 24 which extends through the rear wall 13 of the smokehouse. This duct is provided within the smokehouse with a plurality of downwardly directed nozzles 25 which direct the air downwardly. After passing around the produce the air so discharged is withdrawn through openings 26 in the undersides of overhead ducts 27. Each of these ducts 27 is shown as arranged alongside one of the side walls 10, 11 of the smokehouse and extends through the rear wall 13 thereof.

The air conditioning unit forming the subject of the present invention includes a casing comprising an upper casing section A and a lower casing section B, the casing and its component sections being of box-like rectangular form. The smokehouse and the unit are arranged back to back and hence the upper casing section A includes a rear wall 30, side walls 31, 32, a front wall 33 and a top wall 34, these walls being suitably reinforced with angle bars. Similarly the lower casing section B includes a rear wall 40, side walls 41, 42, a front wall 43 and a bottom wall 44, these walls being likewise suitably reinforced with angle bars. The lower casing section B is supported by removable feet 45 and its lower end is formed to provide a drain pan provided with a drain 46. The two sections A and B are provided around the opposing edges of their side and front walls with horizontal angle bars, indicated generally at 47, these angle bars of the two sections being arranged back to back and providing a convenient means for bolting or otherwise securing the two sections A and B together.

The upper section A houses the scroll 50 of a supply fan, indicated generally at 51, this scroll

having inlets 52 at its opposite sides and an outlet 53 extending through an opening 54 at the upper end of the rear wall 30 of the upper casing section A. The fan wheel 55 arranged within the scroll 50 is mounted on a horizontal fan shaft 56, the ends of which are supported by bearings 57 suitably mounted on the side walls 31 and 32 of the upper section A of the casing. The supply fan is shown as being driven by an electric motor 60, mounted on the top wall 34 of the casing and as having a pulley 61 on its motor shaft, this pulley being connected to a pulley 62 on the fan shaft 56 by a drive belt 63. The outlet 53 of the supply fan is adapted to be directly connected with the rear end of the central overhead supply duct 24 of the smokehouse so that the air and smoke delivered by the supply fan is introduced into the smokehouse through the downwardly directed nozzles 25. The scroll 50 is also preferably provided with an access door 58 for cleaning the fan wheel 55.

Opposite the opening 54 through which the outlet 53 of the fan projects, the front wall 33 of the upper casing section A is formed to provide an opening 64 surrounded by a flanged neck 65, this opening having a removable cover 66 which permits of ready access to the chamber in which the fan is located.

Immediately below the flanged neck 65 a smoke inlet opening 67 is provided, this opening being surrounded by a flanged neck 68 which permits of attachment to a smoke pipe 69, this smoke pipe leading from the usual smoke pot (not shown) which supplies smoke for the operation 35 of the smokehouse. The volume of smoke drawn into the unit through the smoke pipe 69 is controlled by dampers 70 in this pipe, these dampers being under the manual control of a hand lever 71. On the opposite side of the upper casing 40 section A a horizontal perforated pipe 72 is provided, this pipe being perforated as indicated at 73 and being adapted to be connected with a water or steam supply pipe 74 for humidifying the air drawn into the fan 51 when this becomes 45 necessary.

At the extreme open upper end of the lower casing section B a plurality of volume control dampers 75 are provided. Each of these dampers is journaled along its central horizontal axis 50 to the side walls 41 and 42 of the lower casing section B, as best shown in Fig. 4 and are interconnected to work in unison by a horizontal bar 76. The dampers are adjusted by means of a hand lever 77 arranged exteriorly of the casing 55 and connected to the shafts of one of the dampers. This hand lever 77 traverses a segment 78 on the side wall 42 of the lower casing section B, this segment being so designed that the hand lever 77 can be set in any adjusted position and hence hold the volume control dampers 75 in such adjusted position.

A suitable number of heating coil sections, indicated generally at 80, are arranged in the lower casing section B. These heating coil sections 65 can be provided in any number having any desired amount of heating surface and are shown as being three in number, each of the coils comprising a tubular inlet header 81 having a pipe 82 for supplying steam, a tubular outlet header 83 having a condensate outlet pipe 84 and the headers 81 and 83 being connected by a plurality of hairpin tubes 85. To provide improved heat transfer the tubes 85 are preferably fin surfaced, (not shown) these fins being highly polished so as to prevent the deposit of creosote on these fins.

Each of the three coil sections 80 is shown as being independently removable from the lower casing section B and for this purpose the steam connections 82 and 84 for these coils pass through a removable access plate 88 which is secured to the side wall 41 of the lower casing section B around an opening 89 which is of such size as to permit the coil sections 80 to be slid out of the casing after the plate 88 has been removed. To facilitate this removal the individual coil sections are supported within the casing in the manner of drawers on side angle bars 89, these angle bars being secured to the rear and front walls 40, 43 of the lower casing section B. The lower header 83 of each of the coil sections rests upon a corresponding pair of these angle bars 89 and at the opposite or inner end of the coil section, a plate 90 is secured to the hairpin tubes 85 adjacent their return bends, this plate being shown as flanged at its lower end to slidably rest upon the same pair of angle bars 89.

To permit of ready access to the coil sections 80 for the purpose of inspecting or cleaning them while in place, the front wall 43 is provided with a large rectangular opening 91 which is flanged around the margin, as indicated at 92, and to this flange is secured a removable panel 93 providing access to the coil sections 80.

Below the coil sections 80 the lower casing section B is formed to provide a supply chamber 95 for outside and return air, the lower wall of this supply chamber being formed by a horizontal baffle plate 96 which is secured at its opposite ends to the rear and front walls 40, 43 of the lower casing section B, as best shown in Fig. 3, but is spaced from the side walls 41, 42 thereof so as to provide openings 97. Outside air is admitted to this supply chamber 95 through an inlet 100 which is arranged in the front wall 43 of the lower casing section B and discharges the outside air on top of the baffle plate 96. To prevent the bypassing of outside air this inlet 100 is narrower in a horizontal direction than the baffle plate 96, as best illustrated in Fig. 4. This outside air inlet 100 is connected to an outside air duct 101.

Below the baffle plate 96 the lower casing section B is formed to provide an exhaust chamber 105. In this exhaust chamber is arranged the scroll 106 of a static pressure fan, indicated generally at 107, this scroll having inlets 108 at its opposite sides and an outlet 109 extending through an opening 110 in the lower part of the rear wall 43 of the lower casing section B. The fan wheel 111 arranged within the scroll 106 is mounted on a horizontal fan shaft 112, the ends of which are supported by bearings 113 suitably mounted on the side walls 41 and 42 of the lower casing section B of the casing. The static pressure fan is shown as being driven by an electric motor 115 mounted on a removable bracket 116 projecting outwardly from the lower end of the side wall 41 of the casing. This motor is shown as having a drive pulley 117 on its drive shaft, this pulley being connected to a pulley 118 on the fan shaft 112 by a drive belt 119. The outlet 109 from the static pressure fan 107 connects with an exhaust duct 120.

The return air from the smokehouse is introduced into the lower part of the lower casing section B in such manner that a part of this return air is drawn into the supply chamber 95 and the balance is drawn into the exhaust chamber 105 to be discharged by the static pressure fan 107. For this purpose each side wall 41 and

42 of the lower casing section B is provided with a return air inlet 125, each of these inlets leading into the corresponding space 97 at each side of the baffle plate 96 so that the two inlets 125 are intersected by the plane of this baffle plate 96, as best shown in Fig. 4. Each of these inlets 125 is connected by a duct 126 with the end of the corresponding overhead side return duct 21 of the smokehouse, as best shown in Figs. 1 and 2.

Referring to the diagrammatic representation of the control instruments used in connection with the air conditioning unit as above described to regulate the temperature, humidity and static pressure of the air within the smokehouse, the numeral 130 represents an air pressure supply line through which air is supplied at, say 15 pounds pressure, to a static pressure regulator 131 which can be arranged within the smokehouse and to a double pen recording regulator 132. The numeral 133 represents an automatic water pan of a wet bulb thermostat 134 the sensitive part of which is encased with a covering of absorbent material 135, the lower part of which is immersed in the water contained in the automatic water pan 133. The automatic water pan is also arranged to support a dry bulb thermostat 136 and the automatic water pan can be arranged in one of the return air ducts 126 so that the sensitive parts of the wet and dry bulb thermostats are responsive to the wet and dry bulb temperature of the air within the smokehouse.

The control line 140 from the dry bulb thermostat 136 leads to the double pen recording regulator 132 and through this regulator controls the air pressure in a line 141 leading to a diaphragm valve 142 which controls the admission of steam to the bank of heating coil sections 80 in the upper part of the lower section A of the air conditioning unit. The control line 145 from the wet bulb thermostat 134 leads to the double pen recording regulator 132 and through this regulator controls the air pressure in a line 146 leading to a diaphragm valve 147 which controls the supply of water or steam to the perforated humidifying pipe 72 arranged in the upper casing section A of the air conditioning unit. This air pressure line 146 also leads to a motor 148 controlling a set of dampers 149 in one or both of the return air ducts 126 and also leads to a motor 150 controlling a set of dampers 151 in the outside air ducts 101. The motors 148 and 150 work in opposition to each other, the change in pressure in the line 146, under control of the wet bulb thermostat 134, actuating one of these motors to open the corresponding set of dampers and actuating the other motor to close the corresponding set of dampers.

The outlet line 155 from the static pressure regulator 131 controls the damper motor 156 controlling a set of dampers 157 in the exhaust duct 120.

Installation and operation of the air conditioning unit

In installing the air conditioning unit forming the subject of the invention it will be seen that, in shipping the unit to the packing plant and also in getting it through the doors and corridors to the location of the smokehouse in the packing plant the unit can readily be transported by dividing the unit into its two component sections A, B, this merely requiring the removal of the fastenings holding the angle bars 47 together. To further facilitate such transportation the motor 60 for the supply fan can be readily re-

moved; the bracket 116 carrying the static pressure fan motor 115 can also be removed; and the removable feet 45 can also be removed. By this means not only is it possible to ship the unit in a knockdown condition but the assembly of the unit is facilitated inasmuch as the two major sections are of such weight that they can readily be set in position. Further the removability of the feet 45 permits of adjusting the overall height of the unit and its duct openings as may be desired to suit the particular conditions encountered, feet of the desired height being supplied for this purpose.

In installing the unit air conditioner, the unit can be placed directly up against the rear wall of the smokehouse and the outlet 53 of the supply fan placed directly in the central overhead inlet duct 25 of the smokehouse as illustrated, thereby effecting a substantial saving in duct work and avoiding the danger of leakage, loss of heat, and power loss through resistance to air flow. If the conditions surrounding the installation render it desirable to arrange the unit horizontally as on the roof of the smokehouse or in an existing smoke pit below the smokehouse, this can readily be done with the unit. If further peculiar conditions render it desirable to have the supply fan 51 discharge in the opposite direction from that shown, it will be seen that the entire upper section A of the casing can be turned completely around and such reversal readily effected, this requiring but a slight alteration in the attaching flanges 47.

The various motor control dampers 149, 151 and 157 are not, however, built into the unit. These motor operated dampers are purposely mounted in the corresponding ducts leading to or from the unit in order to provide flexibility in supplying any make or form of control desired by the packer.

When once installed the air conditioning unit occupies very little floor and overhead space and is connected with a minimum amount of duct-work.

In the operation of the air conditioning unit smoke is supplied from a suitable smoke pot (not shown) through the smoke pipe 69 into the upper section A of the unit, the admission of the smoke being under manual control of the dampers 70 regulated by the hand lever 71. This smoke is drawn into the inlet 52 of the supply fan 51 together with air drawn from the lower section B of the air conditioning unit under control of the volume control dampers 75 which are manually regulated by the handle 71. The smoke laden air so drawn into the fan 51 is discharged through the outlet 53 of the fan directly into the overhead central duct 24 arranged within the smokehouse and the smoke is discharged downwardly through the nozzles 25. The setting of the volume control dampers 75 controls the amount of air which is introduced into the smokehouse through the nozzles 25; the velocity of the air so introduced, and hence also the secondary motion of the air in the smokehouse induced by these nozzles; and also, to a certain extent, the density of the smoke in this air, this density being determined by the proportional adjustment of these volume control dampers and the smoke dampers 70.

The smoke laden air so discharged downwardly through the nozzles 25 travels around the products contained within the smokehouse to cure and smoke the same. A distinct secondary movement of the air within the smokehouse is also obtained so as to insure adequate air-movement 70

5 to contact with all surfaces of the produce contained within the smokehouse. The air is withdrawn through the outlet openings 26 in the bottom of the overhead side outlet ducts 27 arranged within this smokehouse and is drawn downwardly through the ducts 126, past the control dampers 149 into the return air openings 125 in the lower part of the lower casing section B of the air conditioning unit. These openings 10 are arranged to discharge into the spaces 97 at the sides of the baffle plate 96 and hence a part 15 of this return air enters the supply chamber 95 above this baffle and the other part enters the exhaust chamber 105 below this plate 96. The 20 exhaust chamber 105 is exhausted by the static pressure fan 107, the inlets 108 of which are arranged in this chamber 105 and the outlet 109 of which discharges into the exhaust duct 120, this discharge being under control of the dampers 157.

25 Outside air is also drawn into the supply chamber 95. This outside air is under control of the motor operated dampers 151 in the fresh air duct 101 leading to the outside air inlet opening 100 to this supply chamber 95. In order to prevent short circuiting of this outside air to the exhaust chamber 105, this air is introduced immediately above the baffle 96 at its center and parallel with its major axis so that there is no danger of this outside air flowing down through the openings 97 at the sides of the baffle plate 96 along with the return air being exhausted from the unit, as previously described.

30 The outside air and the return air drawn into the supply chamber 95 mixes and passes up through the several coil sections 80 contained in the upper part of the lower section B of the unit and is heated thereby when heat is required in the air admitted to the smokehouse. This 35 heated mixture of return and outside air is then drawn past the volume control dampers 75 by the supply fan 51, as described at the start of the description of the operation, this heated mixture being also mixed with the smoke supplied through the smoke inlet 67.

40 In the operation of the smokehouse the static pressure regulator 131 is set to maintain a predetermined atmospheric pressure within the smokehouse. This pressure can be set to be either above or below atmospheric pressure.

45 When the static pressure within the smokehouse departs from the setting of the static pressure regulator 131 the static pressure regulator alters the pressure in its outlet line 155 to open or close the dampers 157 in the exhaust duct 120 through the medium of the damper motor 156. The closing of these dampers 157 in the outlet duct 120 from the static pressure fan 107 chokes off the quantity of air relieved from the smokehouse and hence increases the pressure of the air within the smokehouse. Conversely, the opening of these dampers 157 permits a less restricted discharge of the air and hence decreases the pressure of the air within the smokehouse.

50 The temperature maintained within the smokehouse is regulated through a suitable adjustment provided in the double pen recording regulator 132. When the temperature within the smokehouse drops below this setting, the dry bulb thermostat 136 in one of the outlet ducts 126 actuates the double pen recording regulator 132 to adjust the air pressure in its outlet line 141 to open the diaphragm valve 142 and admit an increased amount of steam to the bank of heating coil sections 80 in the lower section B of

the air conditioning unit, this increased temperature of the coils restoring the temperature of the air within the smokehouse to the setting of the double pen recording regulator. Conversely, a rise in temperature in the smokehouse above the setting of the double pen recording regulator effects a shutting off of the diaphragm valve 142 and hence a decrease in the amount of steam admitted to the heating coil sections 80.

The humidity, preferably the absolute humidity, maintained within the smokehouse is regulated through a suitable adjustment provided in the double pen recording regulator 132. When the humidity in the smokehouse rises above the setting of the double pen recording regulator 132, the wet bulb thermostat 134 in one of the outlet ducts 126 actuates the double pen recording regulator 132 to adjust the air pressure in its outlet line 146 to open the dampers 151 in the outside air duct 101, through the medium of the damper motor 150, and at the same time to close the dampers 149 in the return air duct or ducts 126 through the medium of the damper motor 148. This proportionate opening of the outside air dampers and closing of the return air dampers serves to admit a greater proportion of outside air and since the humidity of the outside air is always lower than the humidity maintained within the smokehouse, this opening of the outside air dampers and closing of the return air dampers serves to lower the humidity of the air within the smokehouse. Conversely, when the humidity in the smokehouse drops slightly below the setting of the double pen recording regulator 132, the wet bulb thermostat 134 actuates the double pen recording regulator 132 to adjust the pressure in its outlet line 146 to open the outside air dampers 151 and close the return air dampers 149. Thus, the proportion of humid return air in the mixture delivered to the smokehouse is increased and hence the low humidity therein restored to the setting of the double pen recording regulator 132.

If the humidity in the smokehouse drops below the capacity of the outside and return air dampers 151 and 149 to control, the wet bulb thermostat 134 actuates the double pen recording regulator 132 to adjust the air pressure in its outlet line 146 to open the diaphragm valve 147 and admit water or steam to the perforated humidifying pipe 72 in the upper section A of the unit, this water or steam being discharged through the orifices 73 in this pipe and thereby humidifying the mixed air drawn into the supply fan 51.

When it becomes necessary to inspect, clean or perform any minor repairs on the apparatus contained within the casing of the air conditioning unit, it will be seen that such can readily be done through the several access panels provided in the casing. Thus, by removing the panel 68 in the front wall of the unit the supply fan 51 is rendered entirely accessible for cleaning the same or making any minor repairs. Similarly, the removal of the large panel 83 in this same front wall of the casing renders the entire bank of heating coil sections accessible for cleaning or minor repairs and renders the volume control dampers 75 accessible for similar purposes. If more extensive repairs or cleaning of the heating coil sections 88 is required, the inlet and outlet pipes 82 and 84 for these sections can be disconnected and the plate 88 removed so that any one or all of the heating coil sec-

tions 80 can be slid out of the side of the unit in the manner of a drawer.

Where the smokehouse is operated under conditions demanding a high humidity, a certain amount of condensation necessarily occurs in the bottom of the air conditioning unit through the contact of the humid return air with the relatively cool walls of the unit. This water of condensation flows down these walls into the pan formed at the bottom of the lower section B of the casing and out through the drain 46.

From the foregoing it will be seen that the present invention provides a very simple and compact air conditioning unit containing the necessary mechanisms for supplying air into the smokehouse or similar enclosure; varying the amount and velocity of the air so supplied to obtain the desired movement of both the primary and secondary air therein; introducing smoke to the air so supplied when required; heating the air so introduced when required; withdrawing air from the enclosure to maintain the desired static pressure therein; returning a part of the air so withdrawn together with outside air to maintain the desired humidity in the enclosure; and humidifying the air supplied to the enclosure by the addition of water or steam when required. By the provision of these instrumentalities in a single compact unit the problem of installation is greatly simplified, the cost of the equipment greatly reduced and losses also eliminated. The air conditioning unit as a whole is also rendered adaptable to meet various installation conditions. At the same time a control of increased accuracy can be obtained, particularly in the elimination of the leakage of heat or air and in the elimination of any danger of by-passing of air in the unit.

I claim as my invention:

- 40 1. An air conditioning unit for conditioning the air in enclosures in which materials are processed, comprising a casing, a supply fan secured to said casing and having its inlet communicating with the interior thereof and its outlet adapted to deliver air to said enclosure, means for admitting return air from said enclosure into said casing at the end thereof opposite said supply fan, means adjacent said return air admitting means for admitting outside air into said casing, heating coils arranged in said casing between said supply fan inlet and said return and outside air admitting means for heating the return and outside air drawn into said supply fan, a volume control damper housed in said casing and controlling the total volume of said return and outside air drawn through said casing and into said supply fan, and means for regulating said volume control damper.
- 45 2. An air conditioning unit for conditioning the air in enclosures in which materials are processed, comprising a casing, a supply fan secured to said casing and having its inlet communicating with the interior thereof and its outlet adapted to deliver air to said enclosure, means for admitting return air from said enclosure into said casing at the end thereof opposite said supply fan, means adjacent said return air admitting means for admitting outside air into said casing, heating coils arranged in said casing between said supply fan inlet and said return and outside air admitting means for heating the return and outside air drawn into said supply fan, a volume control damper housed in said casing intermediate said heating coils and said supply fan inlet and controlling the total volume of said return
- 50 3. An air conditioning unit for conditioning the air in enclosures in which materials are processed, comprising a casing, a supply fan secured to said casing and having its inlet communicating with the interior thereof and its outlet adapted to deliver air to said enclosure, means for admitting return air from said enclosure into said casing at the end thereof opposite said supply fan, means adjacent said return air admitting means for admitting outside air into said casing, heating coils arranged in said casing between said supply fan inlet and said return and outside air admitting means for heating the return and outside air drawn into said supply fan, a volume control damper housed in said casing intermediate said heating coils and said supply fan inlet and controlling the total volume of said return
- 55 4. An air conditioning unit for conditioning the air in enclosures in which materials are processed, comprising a casing, a supply fan secured to said casing and having its inlet communicating with the interior thereof and its outlet adapted to deliver air to said enclosure, means for admitting return air from said enclosure into said casing at the end thereof opposite said supply fan, means adjacent said return air admitting means for admitting outside air into said casing, heating coils arranged in said casing between said supply fan inlet and said return and outside air admitting means for heating the return and outside air drawn into said supply fan, a volume control damper housed in said casing intermediate said heating coils and said supply fan inlet and controlling the total volume of said return
- 60 5. An air conditioning unit for conditioning the air in enclosures in which materials are processed, comprising a casing, a supply fan secured to said casing and having its inlet communicating with the interior thereof and its outlet adapted to deliver air to said enclosure, means for admitting return air from said enclosure into said casing at the end thereof opposite said supply fan, means adjacent said return air admitting means for admitting outside air into said casing, heating coils arranged in said casing between said supply fan inlet and said return and outside air admitting means for heating the return and outside air drawn into said supply fan, a volume control damper housed in said casing intermediate said heating coils and said supply fan inlet and controlling the total volume of said return
- 65 6. An air conditioning unit for conditioning the air in enclosures in which materials are processed, comprising a casing, a supply fan secured to said casing and having its inlet communicating with the interior thereof and its outlet adapted to deliver air to said enclosure, means for admitting return air from said enclosure into said casing at the end thereof opposite said supply fan, means adjacent said return air admitting means for admitting outside air into said casing, heating coils arranged in said casing between said supply fan inlet and said return and outside air admitting means for heating the return and outside air drawn into said supply fan, a volume control damper housed in said casing intermediate said heating coils and said supply fan inlet and controlling the total volume of said return
- 70 7. An air conditioning unit for conditioning the air in enclosures in which materials are processed, comprising a casing, a supply fan secured to said casing and having its inlet communicating with the interior thereof and its outlet adapted to deliver air to said enclosure, means for admitting return air from said enclosure into said casing at the end thereof opposite said supply fan, means adjacent said return air admitting means for admitting outside air into said casing, heating coils arranged in said casing between said supply fan inlet and said return and outside air admitting means for heating the return and outside air drawn into said supply fan, a volume control damper housed in said casing intermediate said heating coils and said supply fan inlet and controlling the total volume of said return
- 75 8. An air conditioning unit for conditioning the air in enclosures in which materials are processed, comprising a casing, a supply fan secured to said casing and having its inlet communicating with the interior thereof and its outlet adapted to deliver air to said enclosure, means for admitting return air from said enclosure into said casing at the end thereof opposite said supply fan, means adjacent said return air admitting means for admitting outside air into said casing, heating coils arranged in said casing between said supply fan inlet and said return and outside air admitting means for heating the return and outside air drawn into said supply fan, a volume control damper housed in said casing intermediate said heating coils and said supply fan inlet and controlling the total volume of said return

and outside air drawn through said casing and into said supply fan, and means for regulating said volume control damper.

3. An air conditioning unit for conditioning the air in enclosures in which materials are processed, comprising a casing, a supply fan arranged at one end of said casing and having its inlet communicating with the interior thereof and its outlet arranged to deliver air to said enclosure, means arranged in said casing at the end thereof opposite from said supply fan and forming a supply chamber and an exhaust chamber therein, said supply chamber being in communication with said inlet of said supply fan and said chambers being in communication with each other, means for admitting outside air to said supply chamber, means for admitting return air from said enclosure jointly to said supply and exhaust chambers, an exhaust fan secured to said casing and discharging said return air from said exhaust chamber and heating coils arranged in said casing between said inlet of said supply fan and said supply chamber for heating the outside and return air drawn into said supply fan.

4. An air conditioning unit for conditioning the air in enclosures in which materials are processed, comprising an elongated casing, a supply fan arranged at one end of said casing and having its inlet communicating with the interior thereof and its outlet arranged to deliver air to said enclosure, a baffle plate extending transversely across the interior of said casing at the opposite end of said casing from said supply fan and forming an exhaust chamber at the extreme end of said casing and a supply chamber intermediate said exhaust chamber and said inlet of said supply fan, said supply chamber being in communication with said inlet of said supply fan and said chambers being in communication with each other, means for admitting outside air to said supply chamber, means for admitting return air jointly to said supply and exhaust chambers, an exhaust fan discharging said return air from said exhaust chamber and heating coils arranged in said casing between said inlet of said supply fan and said supply chamber for heating the outside and return air drawn into said supply fan.

5. An air conditioning unit for conditioning the air in enclosures in which materials are processed, comprising an elongated casing, a supply fan arranged at one end of said casing and having its inlet communicating with the interior thereof and its outlet arranged to deliver air to said enclosure, a baffle plate extending transversely across the interior of said casing at the opposite end of said casing from said supply fan and forming an exhaust chamber at the extreme end of said casing and a supply chamber intermediate said exhaust chamber and said inlet of said supply fan, said supply chamber being in communication with said inlet of said supply fan and said baffle plate being spaced from one wall of said casing to provide an opening establishing communication between said chambers, means for admitting outside air to said supply chamber parallel with said baffle plate, means for admitting return air to said opening between said baffle plate and said one wall of said casing, an exhaust fan for discharging said return air from said exhaust chamber and heating coils arranged in said casing between said inlet of said supply fan and said supply chamber for heating the outside and return air drawn into said supply fan.

6. An air conditioning unit for conditioning the air in enclosures in which materials are proc-

essed, comprising a casing, a supply fan arranged at one end of said casing and having its inlet communicating with the interior thereof and its outlet arranged to deliver air to said enclosure; means arranged in said casing at the end thereof

5 opposite from said supply fan and forming a supply chamber and an exhaust chamber therein, said supply chamber being in communication with said inlet of said supply fan and said chambers being in communication with each other, means for admitting outside air to said supply chamber, means for admitting return air from said enclosure jointly to said supply and exhaust chambers, an exhaust fan secured to said casing and discharging said return air from said exhaust chamber, heating coils arranged in said casing between said inlet of said supply fan and said supply chamber for heating the outside and return air drawn into said supply fan, a volume control damper housed in said casing intermediate said heating coils and said supply fan inlet and controlling the total volume of said return and outside air drawn through said casing and into said fan, and means for regulating said volume control damper.

25. 7. An air conditioning unit for conditioning the air in enclosures in which materials are processed, comprising an elongated casing, a supply fan arranged in one end of said casing and having its outlet arranged to deliver air to said enclosure, means arranged in said casing at the end thereof opposite from said supply fan and forming a supply chamber and an exhaust chamber, said exhaust chamber being in communication with said supply chamber and said supply chamber being in communication with the inlet of said fan, means for admitting outside air to said supply chamber, means for admitting return air from said enclosure jointly to said supply and exhaust chambers, an exhaust fan discharging said return air from said exhaust chamber and heating coils arranged in said casing between said supply chamber and said supply fan for heating the outside and return air drawn into said supply fan, said casing being composed of two major separable sections, the first comprising the end of said casing containing said supply fan and the second comprising the end of said casing containing said heating coils and supply and exhaust chambers.

30. 8. An air conditioning unit for conditioning the air in enclosures in which materials are processed, comprising an elongated casing, a supply fan arranged in one end of said casing and having its outlet arranged to deliver air to said enclosure, means arranged in said casing at the end thereof opposite from said supply fan and forming a supply chamber and an exhaust chamber, said exhaust chamber being in communication with said supply chamber and said supply chamber being in communication with the inlet of said fan, means for admitting outside air to said supply chamber, means for admitting return air from said enclosure jointly to said supply and exhaust chambers, an exhaust fan discharging said return air from said exhaust chamber and heating coils arranged in said casing between said supply chamber and said supply fan for heating the outside and return air drawn into said supply fan, said casing being composed of two major separable sections, the first comprising the end of said casing containing said supply fan and the second comprising the end of said casing containing said heating coils and supply and exhaust chambers.

35. 9. An air conditioning unit for conditioning the air in enclosures in which materials are processed, comprising an elongated casing, a supply fan arranged in one end of said casing and having its outlet arranged to deliver air to said enclosure, means arranged in said casing at the end thereof opposite from said supply fan and forming a supply chamber and an exhaust chamber, said exhaust chamber being in communication with said supply chamber and said supply chamber being in communication with the inlet of said fan, means for admitting outside air to said supply chamber, means for admitting return air from said enclosure jointly to said supply and exhaust chambers, an exhaust fan discharging said return air from said exhaust chamber, heating coils arranged in said casing between said supply chamber and said supply fan for heating the outside and return air drawn into said supply fan, a volume control damper arranged in said casing intermediate said heating coils and said supply fan and controlling the volume of said return and outside air drawn into said fan, and means for regulating said volume control dampers, said casing being composed of two major

sections, the first comprising the end of said casing containing said supply fan and the second comprising the end of said casing containing said volume control dampers, heating coils and supply and exhaust chambers.

9. An air conditioning unit for conditioning the air in enclosures in which materials are processed, comprising a casing, a supply fan secured to said casing and having its inlet communicating with the interior thereof and its outlet adapted to deliver air to said enclosure, means for admitting return air from said enclosure into said casing at the end thereof opposite said supply fan, means adjacent said return air admitting means for admitting outside air into said casing, heating coils in said casing between said supply fan inlet and said return and outside air admitting means for heating the return and outside air drawn into said supply fan, a volume control damper housed in said casing and controlling the total volume of said return and outside air drawn through said casing and into said supply fan, means for regulating said volume control damper and means arranged between said volume control damper and said supply fan for humidifying the air drawn into said supply fan.

10. An air conditioning unit for conditioning and supplying smoke laden air to smokehouses, comprising a casing, a supply fan secured to said casing and having its inlet communicating with the interior thereof and its outlet adapted to deliver air to said smokehouse, means for admitting return air from said smokehouse into said casing at the end thereof opposite said supply fan, means adjacent said return air admitting means for admitting outside air into said casing, heating coils arranged in said casing between said supply fan inlet and said return and outside air admitting means for heating the return and outside air drawn into said supply fan, and means arranged between said coils and said supply fan for admitting smoke to said return and outside air drawn into the inlet of said supply fan.

11. An air conditioning unit for conditioning and supplying smoke laden air to smokehouses, comprising a casing, a supply fan secured to said casing and having its inlet communicating with the interior thereof and its outlet adapted to deliver air to said smokehouse, means for admitting return air from said smokehouse into said casing at the end thereof opposite said supply fan, means adjacent said return air admitting means for admitting outside air into said casing, heating coils arranged in said casing between said supply fan inlet and said return and outside air admitting means for heating the return and outside air drawn into said supply fan, means arranged between said coils and said supply fan for admitting smoke to said return and outside air drawn into the inlet of said supply fan, a volume control damper arranged in said casing intermediate said heating coils and said smoke admitting means and controlling the volume of said outside and return air drawn into said supply fan and means for regulating said volume control damper.

12. An air conditioning unit for conditioning and supplying smoke laden air to smokehouses, comprising a casing, a supply fan arranged at one end of said casing and having its inlet communicating with the interior thereof and its outlet arranged to deliver air to said smokehouse, means arranged in said casing at the end thereof

5 opposite from said supply fan and forming a supply chamber and an exhaust chamber therein, said supply chamber being in communication with said inlet of said supply fan and said chambers being in communication with each other, means for admitting outside air to said supply chamber, means for admitting return air jointly to said supply and exhaust chambers, an exhaust fan secured to said casing and discharging said return air from said exhaust chamber, heating coils arranged in said casing between said inlet of said supply fan and said supply chamber for heating the outside and return air drawn into said supply fan and means arranged between said coils and supply fan for admitting smoke to said return and outside air drawn into said supply fan.

10 13. In apparatus for conditioning the air in an enclosure in which materials are processed, and having a casing, a supply fan arranged at one end of said casing and having its inlet communicating with the interior thereof and having its outlet arranged to deliver air to said enclosure, means arranged in said casing at the end thereof opposite from said supply fan and forming a supply chamber and an exhaust chamber therein, said supply chamber being in communication with said inlet of said supply fan and said chambers being in communication with each other, means for admitting outside air to said supply chamber, an outside air damper controlling the admission of said outside air to said supply chamber, means for admitting return air from said enclosure jointly to said supply and exhaust chambers, a return air damper controlling the admission of said return air to said chambers, an exhaust fan secured to said casing and discharging said return air from said exhaust chamber, an exhaust damper controlling the discharge of return air by said exhaust fan, and heating coils arranged in said casing between said inlet of said supply fan and said supply chamber for heating the outside and return air drawn into said supply fan; the combination of means responsive to the dry bulb temperature of the air in the enclosure and controlling the admission of heating medium to said heating coils, means responsive to the humidity of the air in said enclosure and controlling the relative positions of said return air and outside air dampers to control the humidity of the air within the enclosure and means responsive to the pressure of the air within said enclosure and controlling said exhaust damper to maintain a predetermined air pressure in said enclosure.

14. In apparatus for conditioning and supplying smoke laden air to smokehouses, and having a casing, a supply fan arranged at one end of said casing and having its inlet communicating with the interior thereof and having its outlet arranged to deliver air to said smokehouse, means arranged in said casing at the end thereof opposite from said supply fan and forming a supply chamber and an exhaust chamber therein, said supply chamber being in communication with said inlet of said supply fan and said chambers being in communication with each other, means for admitting outside air to said supply chamber, an outside air damper controlling the admission of said outside air to said supply chamber, means for admitting return air from said smokehouse jointly to said supply and exhaust chambers, a return air damper controlling the admission of said return air to said chambers, an exhaust fan secured to said casing and dis-

charging said return air from said exhaust chamber, an exhaust damper controlling the discharge of return air by said exhaust fan, heating coils arranged in said casing between said inlet of said supply fan and said supply chamber for heating the outside and return air drawn into said supply fan, a volume control damper arranged in said casing intermediate said heating coils and said supply fan inlet and controlling the volume of said return and outside air drawn into said supply fan, means for regulating said volume control damper, means arranged between said heating coils and supply fan for admitting smoke to said return and outside air drawn into said supply fan, a smoke damper controlling the admission of said smoke to said smoke admitting means, means for regulating said smoke damper, and means responsive to the dry bulb temperature of the air in the smokehouse and controlling the admission of heating medium to said heating coils; the combination of means responsive to the humidity of the air in said smokehouse and controlling the relative positions of said return air and outside air dampers to control the humidity of the air in said smokehouse and means responsive to the pressure of the air in said smokehouse and controlling the position of said exhaust damper to maintain a predetermined air pressure in said smokehouse.

15. In apparatus for conditioning and supplying smoke laden air to smokehouses, and having a casing, a supply fan arranged at one end of said casing and having its inlet communicating with the interior thereof and having its outlet arranged to deliver air to said smokehouse, means arranged in said casing at the end thereof opposite from said supply fan and forming a supply chamber and an exhaust chamber therein, said supply chamber being in communication with said inlet of said supply fan and said chambers being in communication with each other, means for admitting outside air to said supply chamber,

5 an outside air damper controlling the admission of said outside air to said supply chamber, means for admitting return air from said smokehouse jointly to said supply and exhaust chambers, a return air damper controlling the admission of said return air to said chambers, an exhaust fan secured to said casing and discharging said return air from said exhaust chamber, an exhaust damper controlling the discharge of return air by said exhaust fan, heating coils arranged in said casing between said inlet of said supply fan and said supply chamber for heating the outside and return air drawn into said supply fan, a volume control damper arranged in said casing intermediate said heating coils and said supply fan inlet and controlling the volume of said return and outside air drawn into said supply fan, means for regulating said volume control damper, means arranged between said heating coils and supply fan for admitting smoke to said return and outside air drawn into said supply fan, a smoke damper controlling the admission of said smoke to said smoke admitting means, means for regulating said smoke damper, means responsive to the dry bulb temperature of the air in the smokehouse and controlling the admission of heating medium to said heating coils, and humidifying means arranged between said supply fan and said volume control dampers to humidify the air supplied by said supply fan to said smokehouse; the combination of means responsive to the humidity of the air in the smokehouse and controlling the relative positions of said return air and outside air dampers, means operatively connecting said last means with said humidifying means to control the humidity of the air in said smokehouse and means responsive to the pressure of the air in the smokehouse and controlling the position of said exhaust damper to maintain a predetermined air pressure in said smokehouse.

CHARLES N. DEVERALL.
